UNITED STATES PATENT OFFICE.

HANS Z. NELSON, OF ALBERT LEA, MINNESOTA, ASSIGNOR TO AMERICAN GAS MACHINE COMPANY, OF ALBERT LEA, MINNESOTA, A CORPORATION OF MINNESOTA.

VAPORIZING AND SUPERHEATING INCANDESCENT LAMP.

1,040,388.

Specification of Letters Patent. Patented Oct. 8, 1912.

Application filed May 1, 1912. Serial No. 694,541

To all whom it may concern:

Be it known that I, HANS Z. NELSON, a citizen of the United States, and a resident of Albert Lea, in the county of Freeborn and State of Minnesota, have invented certain new and useful Improvements in Vaporizing and Superheating Incandescent Lamps, of which the following is a specification.

10 This invention relates to devices which are provided with gasoline and air supply pipes, mantles and vaporizers, and with which devices gasoline is vaporized, said vapor mixed with a suitable quantity of air 15 and burned within the mantle, and thereby said mantle is heated to incandescence; and the vaporization of gasoline is thereafter continuously carried on by means of a generating or vaporizing tube which is located 20 within the heat zone of the mantle. And the principal objects of this invention are to obtain a device of the character described which is provided with a removable superheater so situated that gasoline vapor 25 is discharged thereinto from the vaporizer or generator of the device whereby said vapor while flowing through the superheater will have the temperature thereof raised and be discharged from the superheater to the vapor nozzle in a highly heated 30 condition.

A further object is to obtain a Bunsen tube arranged to receive the heated vapor discharged from the nozzle and air at a 35 much lower temperature than said vapor, and said Bunsen tube discharging into a mixing and expanding chamber, where said air will be heated and expanded and thoroughly mixed with the vapor; the discharge 40 end of said mixing and expanding chamber communicating with a vertically disposed combined air and vapor passage way having a burner at the lower end thereof, said burner provided with an inverted mantle 45 thereover.

A further object of the invention is to so dispose the several parts of the device that the air inlet, the Bunsen tube, the mixing and expanding chamber, the needle valve, 50 and the vapor generating passage way of the device will all be contained in a single casting.

A further object of the invention is to associate the said casting with the filter tube

of the device and the coupling by means of 55 which said filter tube is attached to said casting so that the screw threads necessarily required need to be cut with reasonable closeness only, and no gasoline or gasoline vapor can escape therethrough. 60

A further object is to so construct the superheating element of the device that said superheating element, together with the nozzle, may be easily removed from the remainder of the device and when so removed 65 said superheating element and said nozzle may be readily separated from each other.

A further object is to provide means for regulating and cleaning the aperture of the nozzle of the device in such a manner that 70 said aperture will not be enlarged.

A further object is to obtain an economically made device which will have a good appearance, be durable, not liable to get out of order and easily attached to or installed 75 in what is known as the hollow wire system of gasoline lighting.

In the drawing Figure 1 is a top plan view of a device embodying this invention and Fig. 2 is a vertical section on line 2-2 80 of Fig. 1, viewed in the direction indicated by the arrows.

Similar letters refer to similar parts throughout the several figures of the drawing. 85

A is the casing of the device.

B is a casing which I have made by a casting. Casing B is provided with generating or vaporizing passage way b having valve seat b' therein, valve passage way C having 90 needle valve D therein arranged to co-act with valve seat b', air inlet or intake chamber D', vertical tube or passage way E, and mixing and expanding chamber F. The intake chamber D' is provided with air adjusting cap G and said casting is provided with a vertically disposed passage way which is indicated by the lines H in Fig. 2, 95 said passage way being in axial alignment with the tube E. The mixing and expanding chamber F is provided with the discharge aperture f and I is a combined vapor and air conducting tube secured in casting B so that it is vertically disposed, with its upper end in communication with passage 100 way f and its lower end in communication 105 way f and its lower end in communication with burner J.

j is a screen to burner J.

An incandescent mantle attachable to burner J in the ordinary manner is indicated by broken lines K in Fig. 2.

L is a two part casting which is provided with inlet passage way L' and with discharge nozzle L''. Part l is provided with external screw threads which fit into corresponding screw threads in part l'. This construction permits the assembling of parts L, M, M', N and N'. The discharge nozzle L'' is provided with a cylindrical wall which fits closely into but is removable from the passage way in casting B which is indicated by lines H in Fig. 2.

M is a cleaning and regulating needle secured in base M'. Needle M is substantially the diameter of the aperture in nozzle L''. Base M' is movable longitudinally by crank N which is rigidly secured on the end of the spindle N'. Spindle N' is turned as indicated at n so that it may be readily grasped and said spindle rotated to turn the crank pin N and thereby move base M' and thrust needle M into and draw it out of the aperture in nozzle L''.

O is a superheater which I have heretofore constructed of what is known in the art as hollow wire. Superheater O is provided with a coil O' and is provided at one end with the union P by means of which it is attached to casting B so as to be in communication, at its upper end, with vaporizing passage way b in said casting. Said superheater O is also provided at its lower end with the union P' by means of which it is attached to the casting L so as to be in communication with and discharge into passage way L'. This superheater O is removable from casting B by loosening the union P and is removable from casting L by loosening the union P'.

Gasolene is supplied to the device through the filter tube Q. Filter tube Q is provided with filtering material Q'. I have heretofore used asbestos for filtering material. The ends of filter tube Q are ground, as at q, q'. The upper end of the casting B is ground to fit the end q of filter tube Q (see Fig. 2).

R, R', are couplings which are respectively provided with internal screw threads, which screw threads fit corresponding screw threads r on casting B and head T and r' on tube Q. By turning the couplings firmly into place on casting N and head T respectively and turning the filter tube Q well into said couplings R, R', the ends q of said tube Q will fit closely to the seats provided thereon said casting B and head T and gasoline tight joints are obtained. I have placed gaskets lettered S in Fig. 2, between the ends q of said filter tube and the casting B and head T to make sure of getting gasolene liquid and vapor proof joints, and find that I can obtain this result with the screw threads

of said parts Q, R, R' and T and the upper end of casting B ordinarily close fitting. The screw threaded part of casting B to which the collar R is attached, and the head T to which collar R' is attached respectively 70 constitute metal bodies to which the filter tube Q is connected by means of the said collars.

I claim:

1. A casting provided with a vaporizing 75 passage way and with a passage way for a needle valve, said passage ways provided with a valve seat at their intersection, said casting also provided with an air intake chamber, a vertical passage way and a mixing chamber, said vertical passage way communicating with the air intake chamber and with the mixing chamber, and said mixing chamber provided with a discharge passage way, and the said air intake chamber provided with an aperture concentric to the axial line of the vertical passage way, in combination with a superheating pipe provided with a nozzle, said superheating pipe and nozzle removably attachable to said casting so that the passage way in said pipe is in communication with the vaporizing passage way and the discharge opening of the nozzle is concentric to the axial line of said vertical 90 passage way.

2. A casting provided with a vaporizing passage way and with a passage way for a needle valve, said passage ways provided with a valve seat at their intersection, said casting also provided with an air intake 100 chamber, a vertical passage way and a mixing chamber, said vertical passage way communicating with the air intake chamber and with the mixing chamber, said mixing chamber provided with a discharge passage way, and the said air intake chamber provided with an aperture concentric to the axial line of the vertical passage way, in combination with a superheater comprising a hollow wire provided with a coil and a casting having a 110 nozzle thereto and provided with a passage way therethrough, the said nozzle provided with a cylindrical portion fitting in the aperture in the air intake chamber, means to removably attach one end of said hollow 1 wire to one of said castings and means to attach the other end of said hollow wire to the other of said castings, so that the passage way in said hollow wire is in communication with the passage ways in said castings.

3. A filter tube and a casting provided with a passage way therethrough communicating with the filter tube, and provided with a vertical passage way, and air intake chamber communicating with said vertical passage way and a mixing chamber into which said vertical passage way discharges, in combination with a superheater comprising a hollow wire provided with a coil and a casting having a nozzle thereto and pro-

vided with a passage way therethrough, the said nozzle provided with a cylindrical portion fitting in an aperture in the floor of the air intake chamber, means to removably attach one end of said hollow wire to one of said castings and means to attach the other end of said hollow wire to the other of said

castings, so that the passage way in said hollow wire is in communication with the passage ways in said castings.

HANS Z. NELSON.
